(57) **CLAIM**

We claim, the ornamental design for a water purification media device, as shown and described.

DESCRIPTION

FIG. 1 is a front top perspective view of a first embodiment of the design;

FIG. 2 is a front view of the embodiment of FIG. 1, the rear view and the side views are the same as the front view;

FIG. 3 is a top view of the embodiment of FIG. 1;

FIG. 4 is a bottom view of the embodiment of FIG. 1;

FIG. 5 is a front bottom perspective view of the embodiment of FIG. 1;

FIG. 6 is a front top perspective view of a second embodiment of the design;

FIG. 7 is a front view of the embodiment of FIG. 6, the rear view and side views being the same as the front view; and, FIG. 8 is a top view of the embodiment of FIG. 6, the bottom view being the same as FIG. 4.

References to “side”, “top”, “front”, “rear” and “bottom” in the figure descriptions are not meant to require certain in-use orientation; a water purification media device according to the claimed design may be used in any orientation.

1 Claim, 8 Drawing Sheets
